UNITED STATES PATENT OFFICE.

HENRY A. HILLS, OF GRAND RAPIDS, MICHIGAN

DISTILLATION PROCESS.

1,414,465.

Specification of Letters Patent.

Patented May 2, 1922.

Application filed May 7, 1917. Serial No. 187,017.

To all whom it may concern:

Be it known that I, HENRY A. HILLS, a citizen of the United States, and a resident of the city of Grand Rapids, in the county of Kent and State of Michigan, have invented certain new and useful Improvements in Distillation Processes; and I do hereby declare that the following is a full, clear, and exact description of the same, reference being had

10 to the accompanying drawings, and to the numerals of reference marked thereon, which form a part of this specification.

This invention relates to an improved distillation process and construction of a still, 15 particularly designed for use in cleaning establishments and for other similar purposes where it is desired to purify the cleaning agent or liquid, as for instance gasoline or benzine, after the same has been used. Many 20 other different types of stills have been designed for the recovery of cleaning fluid by distillation, some operating by what is known as the "wet" process, which involves the direct introduction of a jet of steam, and 25 others operating by what is known as the "dry" process, involving the use of steam coils for heating the fluid in the still.

The objection to the dry method wherein the steam coils only are used is that the contents of the still remain relatively quiescent 30 until a generation of gas takes place, and as a consequence, a foaming and bubbling of the contents results which builds up and carries the dirt over with the distilled vapor, 35 and as a consequence, a dirty product is obtained.

The objection to the wet method of distillation is that a large percentage of water of condensation becomes mixed with the distillate, and furthermore, the efficiency of the process is low as the method involves the use of a considerable amount of steam for introduction into the fluid to be distilled.

This invention relates to an improved distilling process and its related type of still designed to operate both with a steam heating coil and also with a jet of live steam which is blown directly into the liquid through a special steam mixing nozzle. In 45 this invention a steam coil is disposed in the lower end of the still together with a steam jet of novel construction for introduction of live steam into the contents of the still to agitate the same and cause a rapid circulation 50 and flow about the steam coils which are disposed within the still.

It is an object therefore of this invention to provide a distilling process wherein a valved arrangement of steam coils and a steam jet for the introduction of live steam into the contents of a still is provided so that a most efficient operation of the still may be obtained for the recovery of the volatile liquid.

It is furthermore an important object of this invention to provide a still equipped with heating steam coils in the lower end thereof and with the lower end of the still constructed to facilitate drawing off the residue after a distilling operation and with a steam jet of special construction mounted in the lower end of the still to cause a rapid agitation and circulation of the contents of the still, and yet obviating pounding, and together with said coils, provided with a valve for the control of the flow of steam therethrough.

It is finally an object of this invention to provide a new distillation process and to construct a still in accordance therewith provided with steam coils and a nozzle for the introduction of live steam into the contents of the still heated by said steam coils for the rapid and efficient distillation of fluids to be recovered from the still.

The invention (in a preferred form) is illustrated in the drawings and hereinafter more fully described.

In the drawings:

Figure 1 is a side elevation of a complete distillation apparatus of which a still embodying the principles of my invention forms a part.

Figure 2 is a detail sectional view partly broken away taken on line 2-2 of Figure 1, with parts in elevation.

Figure 3 is a detail section taken on line 3-3 of Figure 2.

Figure 4 is a detail section taken on line 4-4 of Figure 2, with parts omitted.

Figure 5 is a detail section taken on line 5-5 of Figure 4.

As shown in the drawings:

The reference numeral 1, indicates as a whole a frame on which is mounted a reservoir or tank 2, containing the fluid to be distilled. The still itself consists of a cylindrical tank section 3, which is also mounted upon the frame work 1, held secured thereon by bracket arms or braces 4, and at its upper end is provided with a conical top 5, into which an outlet pipe 6, for the distillate is

2

provided. A conical bottom member 7, is provided upon the lower end of the cylindrical tank 3, with an apex thereof offset or at one side as clearly shown in Figure 2, and communicating into the offset apex, is an outlet pipe 8, provided with a valve 9. Mounted in the lower end of the still within the conical bottom section 7, is a steam coil 10, the inlet of which on the exterior coil 10, the inlet of which on the exterior 10 of the still is provided with a valve 11, controlling the supply of steam from a steam supply line 12. The outlet or exhaust line for the steam coils 10, is denoted by the reference numeral 13, and is provided with 15 a valve 14. A steam nozzle for the introduction of live steam is mounted within the still intermediate the steam coils 10, as clearly shown in Figure 2, and consists of a section of pipe 15, which is threaded into 20 a coupling 16, secured in sealing relation through an aperture in the side wall of the still bottom section 7. Secured upon said pipe section 15, spaced therefrom and extending beyond the inner end thereof, is a 25 cylindrical shell 17, provided with holes 18, near the point of connection thereof with said pipe 15. Also connected into said coupling 16, on the exterior of the still, is an inlet steam pipe 19, provided with a valve 30 20, to control the flow of steam thereinto from the steam line 12, with which the same is connected.

The outlet pipe 6, from the still leads into a condenser 21, also mounted upon the frame support 1, adjacent the still, and, at the bottom of the condenser, a draw-off pipe 22, is provided, leading into a separator 23, wherein the oil and water are separated from one another after condensation. An 40 inlet pipe 24, is provided communicating into the lower end of the condenser to admit the cooling fluid thereinto and an outlet pipe 25, is provided near the upper end of the condenser for exit of said cooling fluid. 45 A vent pipe 26, leads upwardly from the separator 23, and together with another vent pipe 27, connected into the reservoir tank 2, is connected to a common vent pipe 28.

50 As clearly shown in Figure 1, an inlet pipe 29, provided with a valve 30, communicates through a T 31, connected into the bottom of the reservoir tank 2, by which the fluid to be distilled for recovery is admitted into said tank 2. Also connected into said T 31, is a draw-off pipe 32, by which the fluid to be purified may be drawn from said tank 2, and conducted into the still 3, said pipe being provided with a valve 33.

60 The operation is as follows:

The fluid to be treated for recovery is run into the reservoir tank 2, through the pipe 29, by opening the valve 30, and closing the valve 33, which controls the outlet 65 from said tank 2. After closure of the inlet

valve 30, the outlet valve 33, is opened to permit a quantity of the fluid to flow into the still 3, after which said valve 33, is closed. The steam valve 11, is then opened to admit steam into the steam coils 10, and if a high grade of distillate is desired the still is operated as a dry still (with the steam coil only). As soon as the flow begins to check however, owing to the higher boiling point, the steam valve 20, is also 70 opened to admit live steam directly into the contents of the still through the steam nozzle 15-17. The passage of steam through this nozzle draws the liquid into the nozzle through the holes 18 and then expels it 75 forcibly, causing the mixed steam and liquid to impinge against the further side of the sloping bottom 7, whence it is deflected upwardly. This creates a circulation of the liquid in a vertical plane, and consequently 80 prevents the accumulation of froth and scum on the surface.

Moreover, the combined vapor pressures of the steam and the heated fluid cause a 85 more efficient distillation, due to the fact 90 that both fluids will distill over at a boiling point lower than that of either of the ingredients separately. By proper manipulation of the respective steam valves 11 and 20, an effective and efficient heating of the 95 contents of the still is assured to obtain the most efficient distillation of the volatile fluid, while the dirt and sediment and other matter settles to the bottom of the still, and may be drawn off from time to time through 100 the pipe 8, by opening the valve 9.

The combination of wet and dry methods of distillation, that is, the use of the steam nozzle for introduction of live steam and the steam coils for the dry heating of the 105 contents of the still, insures a highly efficient process for the recovery of the volatile cleaning fluid. The peculiar construction of the steam nozzle 15-17, prevents pounding as the steam is introduced, and the use 110 of the steam nozzle together with the heating coils breaks up the bubbling and foaming effect which would otherwise take place were the steam coils 10, only used, as the 115 bubbling and foaming effect sometimes floats the dirty matter and sediment over through the outlet pipe of the still with the volatile distillate.

The volatile fluid leaving the still, containing a certain quantity of water vapor, 120 enters the condenser 21, where the same is condensed, and then flows outwardly at the lower end thereof into the separator 23, wherein the water and volatile liquid or oil 125 are separated from one another.

I am aware that various details of construction may be varied through a wide range without departing from the principles of this invention, and I therefore do not purpose limiting the patent granted 13

otherwise than necessitated by the prior art.

I claim as my invention:

1. A distillation process including heating liquid in a still having an inclined bottom and simultaneously propelling a part of the liquid horizontally against the inclined bottom to produce a circulation of the liquid in a vertical plane and thereby aid in the vaporization of the latter and inhibit foaming.
2. A distillation process including heating liquid in a still having an inclined bottom and simultaneously churning up the liquid by injecting live steam against the inclined bottom of the still and thereby aid in the vaporization of the latter and inhibit foaming.
3. A distillation process including heating liquid in a still having an inclined bottom, sucking liquid by means of a steam injector from a point adjacent the bottom of the still and projecting it hori-

zontally at a higher point in the still and against the inclined bottom thereof, thereby churning up the liquid for the purpose of aiding vaporization of the same and inhibiting foaming.

4. A distillation process including heating liquid in a still having an inclined bottom, sucking liquid from a point adjacent the bottom of the still and projecting it horizontally at a higher point in the still and against the inclined bottom thereof to produce a circulation of the liquid in a vertical plane in order for the purpose of aiding the vaporization of the latter and inhibiting foaming.

In testimony whereof I have hereunto subscribed my name in the presence of two subscribing witnesses.
